Patented June 6, 1922.

Application filed January 24, 1922. Serial No. 341. Term of patent 14 years.

To all whom it may concern:

Be it known that I, LOUIS J. MALONE, a citizen of the United States, residing at Riverside, in the county of Burlington and State of New Jersey, have invented a new, original, and ornamental Design for Fraternal Emblems, Medallions, Badges, Buttons, Pins, or Articles of Similar Nature, of which the following is a specification, reference being had to the accompanying drawing, forming part thereof, which shows the design embodied in a medallion constituting a fraternal emblem.

It is to be understood however, that my present ornamental design is applicable not alone to medallions of the character indi-

cated, but is intended, and is equally well suited for the ornamentation of other articles of manufacture requiring surface ornamentation.

I claim:

The ornamental design for a fraternal emblem, medallion, badge, button, pin, or article of similar nature, substantially as shown.

In testimony whereof I affix my signature in the presence of two witnesses.

LOUIS J. MALONE.
